(57) **CLAIM**

The ornamental design for a monitor panel for a construction vehicle, as shown and described.

DESCRIPTION

FIG. 1 is a front, top and right side perspective view of a monitor panel for a construction vehicle showing our new design;

FIG. 2 is a rear, bottom and left side perspective view thereof;

FIG. 3 is a rear view thereof;

FIG. 4 is a left side elevational view thereof;

FIG. 5 is an enlarged view of the portion indicated by lines 5-5 in FIG. 2;

FIG. 6 is an enlarged view of the portion indicated by lines 6-6 in FIG. 4;

FIG. 7 is an enlarged cross-sectional view of the portion indicated by lines 7-7 in FIG. 3, taken along line 7-7 in FIG. 4 with the internal structure omitted; and,

FIG. 8 is a referential view showing the article in use.

The features shown in broken lines in the drawings depict environmental subject matter only and form no part of the claimed design. The dot-dashed lines denote the boundary of the claim and form no part of the claimed design.

1 Claim, 8 Drawing Sheets
